CLAIM

The ornamental design for a housing for magnetic garment fastener, as shown and described.

DESCRIPTION

FIG. 1 is an exploded front elevational view of a housing for a magnetic garment fastener showing the two components of the fastener separated from each other;

FIG. 2 is an exploded rear elevational view thereof;

FIG. 3 is a bottom plan view thereof;

FIG. 4 is an exploded right side elevational view thereof;

FIG. 5 is an exploded left side elevational view thereof;

FIG. 6 is a top plan view of one component of the housing for a magnetic garment fastener;

FIG. 7 is a top plan view of the second component of the housing for a magnetic garment fastener;

FIG. 8 is a first perspective view of the housing for a magnetic garment fastener in an open condition with the two components in close proximity;

FIG. 9 is a second perspective view of the housing for a magnetic garment fastener in an open condition with the two components in close proximity; and,

FIG. 10 is perspective view of the housing for a magnetic garment fastener in a closed condition.

1 Claim, 7 Drawing Sheets
